SAND TOY

Lillian G. Wightman, Hammond, Ind.

Application August 25, 1932, Serial No. 630,398

7 Claims. (Cl. 46—37)

This invention relates to an educational toy consisting of the combination of a plurality of grotesque figure casings representing characters of a story, in combination with a book, and has for one of its principal objects the provision of means for releasably attaching the figure casings to the pages of the book.

Another important object of this invention resides in the provision of means whereby the figures may be taken from the book and distended by filling with sand, or the like.

10 Another still further important object of this invention is the provision of means whereby an automatically closing aperture is used for filling the figure casings with sand.

Another and still further important object of the educational toy of this invention is the provision of means for inverting the filling funnel to empty the casing.

20 Still another and further important object of this invention resides in the provision of means for mounting the casing, filled with sand or the like, on a skid-board for pulling or propelling the same.

25 Other and further important objects of this invention will be apparent from the disclosures in the accompanying drawing and following specification.

This invention, in the preferred form, is illustrated in the drawing, and hereinafter more fully described.

In the drawing:

Figure 1 is a top plan view of the open book of this invention and shows the position of the figure casing on the page.

Figure 2 is an enlarged sectional view of the head of the figure toy with parts broken away, and shows particularly the filling and attaching means.

40 Figure 3 is a perspective view of the figure filled with sand and mounted on the skid-board.

Figure 4 is an end view of the skid-board and shows the method of operating the hinged member for vertically positioning and supporting the 45 toy figure when stuffed.

Figure 5 is a side elevation of the skid-board showing the upright raised.

Figure 6 is a perspective view of the book and shows the method of packing the skid-board 50 therein for transportation.

Figure 7 is a front view of the filling aperture.

Figure 8 is a side view of the head and shows the funnel inverted for emptying purposes.

55 As shown in the drawing:

The reference numeral 10 indicates in a general way a book, which in the preferred form, has pages constructed of oil-cloth, linen, canvas, or similar material. The covers of the book are preferably stiffer and also constructed of any 60 suitable flexible material. Secured to the covers of the book to facilitate handling and to hold the book closed as it is carried, are handles 12 and 13.

In the drawing illustrating the educational toy 65 of this invention, the figure casing of a duck only is shown. It will be apparent, however, that casings representing other birds, animals, persons or the like may be used.

In the preferred embodiment of this invention, the book is constructed so that when the book is open the pages on the left, as at 14, carry the title and such descriptive or educational matter as is desirable, and the pages on the right, as designated by 16 in Figure 1 are illustrated. 70 This illustration includes a suitable background and superimposed thereon is a figure casing 18 which comprises a part of the illustration. This figure casing is preferably constructed of doubled cloth, oil-cloth or the like and sewed to be sand 80 tight. An upwardly extending pocket or sheath in the lower portion of the casing 28 provides a means for mounting the casing itself on the erectable member 38 of the skid-board, as shown by the dotted lines in Figure 3. While this 85 sheath is shown by the dotted lines in Figure 3 as being of triangular shape and centrally located in the bottom of the casing, it will be obvious that a differently shaped member to function in a similar manner may be placed in any 90 location on the lower portion of the casing so long as the opening extends from the bottom of the casing upwardly.

A hook 22 as best shown in Figure 2 is secured to the upper portion of the figure casing 18 and 95 provides a means for attaching said figure casing to the page. A horizontal slit 20 at the top of the page 16 co-acts with the hook 22 to hold the casing 18 when empty, in its proper position on the page. A keeper 24 near the bottom of the 100 page 16 releasably secures the lower portion of the figure 18 to the book.

In the present illustration a scoop 26 used in filling the casing with sand, is positioned on the wing of the duck by slipping said scoop under 105 the loop 28. However, the scoop may be placed in various positions on the other figure casings.

The opening 30 for filling the casing with sand is in the mouth or bill of the figure. This opening is closed when in the normal position, and 110

is so held by a flexible wire 32 sewed in and forming the edge of the opening. (Figure 2.)

The opening operation for filling is performed by a slight pressure on the top and bottom of 5 the bill as shown in Figure 7.

Positioned within the opening 30 and secured to the casing, as best shown in Figure 2, is a collapsible funnel shaped tube 34 which is used in both filling and emptying the casing. This tube, 10 in collapsing, also prevents the sand from sifting through the opening 30. In removing the sand from the casing, the funnel shaped tube 34 is inverted and drawn out as is shown in the drawing in Figure 8. This is accomplished by 15 opening the edge of the bill as shown in Figure 7 and withdrawing the tube 34 with the finger. With the mouth held open and the tube down the sand is easily removed.

A sheet metal skid-board 36, the front end of 20 which is slightly upturned is provided and the forward edge is perforated for attaching a cord. With the cord the skid-board may be towed over the sand or beach.

Hingedly positioned on the skidboard and 25 forming a part thereof is a triangular member 38 which, when desired, is held in an upright position by the braces 40 and 42, the ends of which fit into slots 43, as best shown in Figures 4 and 5. When not in use the member 38 and the 30 braces 40 and 42 may be folded to one side of the skid-board 36 and the whole placed in the pocket 44 of the book 10, as illustrated by Figure 6. While in the preferred form the member 38 is shown as a separate piece hingedly mounted on 35 the skid-board 36, it will be obvious that any other suitable construction may be used. Such, for instance, as a portion of the skid-board itself hingedly secured to the remainder, may be erected to form a support for the casing 18.

40 In order to use the skid-board for carrying the figures, the member 38 is raised and secured by the braces 40 and 42 as shown in Figure 4. The figure is then positioned on the upright member as shown in Figure 3 and may be towed over the 45 sand or beach.

It will be apparent from the foregoing that 50 herein is provided a novel sand toy which is both entertaining and striking. Moreover, there is provided an educational book wherein the characters forming a part of the illustrations in the book may be taken therefrom and used as toys.

Furthermore, on account of the collapsible funnel shaped tube and the spring closed opening which positively prevent the sand from escaping, the toy may be used indoors and on carpets or rugs without damage thereto.

55 I am aware that many changes may be made, and numerous details of construction varied throughout a wide range without departing from the principles of this invention, and I, therefore, do not purpose limiting the patent granted hereon otherwise than as necessitated by the prior art.

I claim as my invention:

65

70

75

1. A sand toy including a skid-board, a casing, an upwardly extending sheath on the lower portion of the casing, means for filling the casing with sand, means for mounting the filled casing on the skid-board for transportation, and means for retaining the sand therein. 80

2. An inflatable toy including a skid-board, a casing, an upwardly extending sheath on the lower portion of the casing, means for filling the casing with sand, means for retaining the sand therein, and means for positioning and maintaining the filled casing on the conveying skid-board. 85

3. An inflatable sand toy including a skid-board, a casing, an upwardly extending sheath on the lower portion of the casing, means for filling said casing with sand, said means including a scoop mounted in the casing and means for mounting the filled casing on the skidboard for transportation, said last named means including an upright member on the skidboard and a co-acting pocket in the casing, and an expandible opening in the casing. 90

4. A toy including a skid-board, an erectable member hingedly mounted thereon, a casing having a sheath adapted for positioning on the member for transportation purposes, means for filling said casing with sand, and means for retaining the sand therein. 95

5. A sand toy including a skid-board, an erectable member hingedly mounted thereon, means for maintaining said member in a vertical position, a casing, an upwardly extending sheath on the lower portion of the casing, means for filling the casing with sand, means for retaining the sand therein, and means for positioning the casing on the member for transportation. 100

6. A sand toy including a skid-board having a plurality of slots on its upper surface, a member hingedly mounted thereon, means for maintaining said member in a vertical position, said means comprising braces, hingedly secured to the member and engageable with slots in the upper surface of the skid-board, a casing, means for filling the casing with sand, means for retaining the sand therein, and means for positioning the casing on the upright member for conveyance to another location. 110

7. A sand toy including a skid-board having a plurality of slots on its upper surface, a member hingedly mounted thereon, means for maintaining said member in a vertical position, said means comprising braces hingedly mounted on the member and adapted to engage the slots, a casing, an upward extending sheath on the lower portion of the casing, means for filling the casing with sand, means for retaining the sand therein, and means for positioning and maintaining the casing on the upright member for transportation of another location. 125
